UNITED STATES PATENT OFFICE.

DUDLEY S. SEYMOUR, OF OAK PARK, ILLINOIS, ASSIGNOR TO UNION SPECIAL MACHINE COMPANY, OF CHICAGO, ILLINOIS, A CORPORATION OF ILLINOIS.

FEEDING MECHANISM FOR FILLED-BAG-SEWING MACHINES.

1,403,874.

Specification of Letters Patent. Patented Jan. 17, 1922.

Application filed November 21, 1917. Serial No. 203,155.

To all whom it may concern:

Be it known that I, DUDLEY S. SEYMOUR, a citizen of the United States, residing at Oak Park, in the county of Lake, State of Illinois, 5 have invented certain new and useful Improvements in Feeding Mechanism for Filled-Bag-Sewing Machines, of which the following is a description, reference being had to the accompanying drawing and to the 10 figures of reference marked thereon.

The invention relates to new and useful improvements in a filled bag sewing apparatus and more particularly to the means for conveying the bag to the stitching mechanism.

An object of the invention is to provide a filled bag sewing apparatus having means for supporting and conveying the filled bag to the stitching mechanism with an endless 20 conveying means for also supporting and conveying the mouth of the bag so that the line of stitching formed in the mouth of the bag will be straight and parallel with the upper end of the bag.

25 A further object of the invention is to provide an apparatus of the above character wherein the supporting means for the mouth of the bag is in the form of an endless belt having supporting pins or the like for holding the mouth of the bag.

A still further object of the invention is to provide an apparatus of the above character with means for stripping the mouth of the bag from supporting pins.

35 In the drawings, which show by way of illustration one embodiment of the invention:—

Figure 1 is a perspective view of a portion of a filled bag sewing apparatus embodying 40 my improvements;

Figure 2 is a front view of the same, with parts of the sewing apparatus omitted, together with the driving mechanism therefor, for the sake of clearness;

45 Figure 3 is a plan view of the parts shown in Figure 1;

Figure 4 is a detail showing the end of the sewing machine arm and the position of the traveling supporting device for the mouth of 50 the bag; and

Figure 5 is a front view of the bag sewing apparatus.

Prior to my invention, a filled bag sewing apparatus has been provided for closing the 55 mouths of bags, which includes a frame hav-

ing a support for the filled bag and an overhanging sewing head containing stitching mechanism and feeding mechanism. The bag is fed along the support therefor by an endless conveyor which travels in timing 60 with the feeding mechanism of the sewing machine. An example of such apparatus is shown in the patent granted to John Bigelow, December 31, 1907, No. 875,314.

The present invention is directed to an 65 improved means for supporting the mouth of the bag as it is presented to the stitching mechanism, to insure that the line of stitching shall be straight and parallel with the upper end of the bag. This improved means 70 consists of an endless band or chain having a plurality of supporting pins on which the mouth of the bag is impaled. This endless band travels in a fixed path, and, therefore, will support and convey the mouth of the 75 bag to the stitching mechanism and also away from the stitching mechanism, so as to insure a straight line of stitching being formed in the closing of the mouth of the bag.

80 Referring more in detail to the drawings, I have shown my invention as applied to a filled bag sewing apparatus having a frame 1, on which is mounted a bag support consisting of a supporting table 2 and an endless conveyor 3. This conveyor runs over rollers 4 and 5 carried by the frame.

Extending upwardly from the frame is the standard 6 on which is mounted a vertically adjustable bracket 7. The sewing head 90 indicated at 8 is bolted to this adjustable bracket. This sewing head includes a standard having an overhanging arm 9 and a work supporting arm 10. The sewing head overhangs the bag support.

95 Mounted in the work arm is a feeding mechanism, the feed dog of which is indicated at 11. This feeding mechanism is of the usual construction and imparts a four-motion movement to said feed dog. The 100 sewing machine includes also a stitching mechanism having a needle 12 carried by the needle bar 13. The needle bar is reciprocated in the usual way and a threaded looper or other complemental stitch-forming mechanism cooperates with the needle in forming a series of stitches.

The parts of the sewing machine are driven by a shaft 14. A belt wheel 15 is mounted on this shaft. The filled bag appa- 110

5 ratus includes a vertical drive shaft 16, on which is mounted a pulley 17. The pulley 17 is supported on the bracket 7 by a bracket 18 and is splined to the shaft 16 so as to turn therewith. A belt 19 runs over the pulleys 17 and 15, and thus imparts driving motion to the feeding and stitching mechanisms of the sewing head.

10 The vertical shaft 16 is driven by a pulley 50 which has a clutch connection with said shaft. The shaft 16 also has a worm gear connection with a cross shaft 52 and this cross shaft has a sprocket chain connection with the roller 4 for driving the conveyor belt 3. The rollers 4 and 5 are carried by a bracket which is bodily adjustable vertically by the screw shafts 53, 53. The worm driving connection is splined to the shaft 16 to permit of this adjustment without disturbing the driving connections for the conveyor.

15 I have indicated in the drawings a filled bag at B. The mouth of this filled bag is directed to the stitching mechanism and a line of stitching formed therein for closing the same. In order that this line of stitching will be straight across the bag, as above noted, I have provided a supporting means or conveyor for the mouth of the bag, which is located adjacent the bag mouth position 20 and travels with the bag and in synchronism with the feeding mechanism of the sewing head and also in synchronism with the conveyor belt. This means consists of an endless band 20 which runs over supporting wheels 21 and 22. The axes of these wheels are vertical and one wheel is located in front of the stitching mechanism and the other in rear thereof. The band is provided with a series of spaced pins 23. The 25 wheels 21 and 22 are carried by a bracket 24. The bracket 24 is formed with a base 25 bolted to the bracket 7, above referred to. Said bracket 24 has two projecting arms which are formed with bearings 26 and 27, 30 respectively.

35 A short stub shaft is mounted in the bearing 26 and carries the wheel 21. A shaft 28 is mounted in the bearing 27 and in a bearing 29 carried by an arm 30 projecting from the base 25 of the bracket 24. The wheel 22 is mounted on this shaft 28. The shaft 28 is given an intermittent rotary movement by means of a friction clutch 31. The movable arm of the clutch is oscillated 40 by a link 32 driven by an eccentric 33 on the main shaft 14 of the sewing machine.

45 Through this friction clutch the shaft 28, as above noted, will be intermittently moved, and this will impart a step-by-step movement to the band 20. The band 20 is an endless band, as noted, and passes across the work support traveling in a groove 34 formed in the work supporting arm 10 and above the feed dog 11 so as not to interfere with the 50 feeding and stitching mechanisms of the sewing head.

55 This groove tends to guide the band and also positions the bag in the proper vertical plane. The band is made of material sufficiently rigid so as to support the mouth of the bag in a straight line, and as 60 the mouth of the bag is impaled on the pins it will be held without sagging and carried straight through the machine so a straight line of stitching will be formed therein.

65 A bar 34* extends along the path of travel 75 of the bag at the right of the sewing head and backs up the band so that pressure may be exerted against the bag mouth to cause the same to be perforated by the pins and impaled thereon.

70 A projecting arm 35 is mounted on the bearing 27. This arm carries an inclined shoe 36, slotted at 37 to permit the band and the pins to pass through the shoe. The shoe extends across the path of travel 85 of the band and serves as a means for stripping the bag from the pins.

75 In the operation of my device, the bag is set on the traveling conveyor 3 and the mouth is impaled on the supporting pins 23. 90 The travel of the band 20 together with the conveyor presents the bag to the sewing head. As soon as the bag reaches the sewing head, the feed will engage the mouth of the bag, and as this feed travels in synchronism with the step-by-step movements 95 of the band and the continuous movement of the conveyor, the bag will be carried through the sewing head. The supporting band holds the mouth of the bag up and insures 100 that it will pass through the head in a straight line, so that the stitching formed in the mouth of the bag will be straight and parallel with the upper end of the bag.

105 It is understood, of course, that in this type of machine the operator stands in front of the sewing head, or near the same, and by reason of the fact that the head overhangs the frame and the conveyor, which carries the weight of the bag, the operator 110 may have ready access to the bags to be stitched, placing the same on the open sided conveyor and impaling the mouth of the bag on the pin conveyor therefor.

115 It will be understood, of course, that an automatic clipper may be used in connection with this filled bag sewing apparatus for clipping the enchain loops between the filled sacks, so as to facilitate the automatic stripping of the sacks or bags from 120 the pin conveyor. One type of automatic clipper which would be suitable for this purpose is shown and described in my prior Patent No. 1,170,349, granted February 1st, 1916.

125 From the above it will be noted that the sewing head and endless band for supporting the mouth of the bag may be simultaneously adjusted vertically. Also the endless conveyor may be vertically adjusted. By these 130

adjustments different size bags may be readily closed.

Having thus described my invention, what I claim as new and desire to secure by Letters Patent, is:—

1. A filled bag closing apparatus including in combination, a supporting frame, a sewing mechanism which includes a feeding mechanism and is supported on said frame 10 and overhangs the front edge thereof, and an endless bag conveyor located adjacent the bag mouth position for supporting and presenting the mouth of the bag to said sewing mechanism, and means for moving said conveyor in synchronism with the feeding mechanism.

2. A filled bag closing apparatus including in combination, a supporting frame, a sewing mechanism which includes a feeding 20 mechanism, means for supporting said sewing mechanism on said frame whereby the same overhangs the front edge of said frame, a support for the bottom of the bag disposed in advance of the front edge of 25 said frame and under said sewing mechanism, an endless bag conveyor located adjacent the mouth of the bag position for supporting and presenting the mouth of the bag to said sewing mechanism, and means 30 for moving the endless conveyor in synchronism with the feeding mechanism.

3. A filled bag closing apparatus including in combination, a supporting frame, a sewing mechanism which includes a feeding 35 mechanism and is supported on said frame and overhangs the front edge thereof, an endless bag conveyor located adjacent the bag mouth position for supporting and presenting the mouth of the bag to said sewing mechanism, means for moving said conveyor in synchronism with the feeding mechanism, and means for adjusting the 40 sewing head and endless bag conveyor.

4. A filled bag closing apparatus, including in combination, a supporting frame, a sewing head supported on said frame and overhanging the front edge thereof, said sewing head including a stitching mechanism and a feeding mechanism, a horizontal 45 support for the bottom of the bag disposed in advance of the front edge of said frame and under said sewing head, an endless conveyor located in front of said frame and above said bag support for supporting and 50 presenting the mouth of the bag to the sewing head and driving connections between the feeding mechanism of the stitching mechanism and the endless conveyor mechanism for operating said mechanisms in synchronism.

5. A filled bag closing apparatus including in combination, a supporting frame, a sewing head supported on said frame and overhanging the front edge thereof, a sup-

port for the bottom of the bag disposed in 65 advance of the front edge of said frame and under said sewing head, and an endless conveyor located in front of said frame and above said bag support and having a plurality of pins for supporting and presenting 70 the mouth of the bag to said sewing head, and means whereby the sewing head and the bag support may be relatively adjusted vertically.

6. A filled bag closing apparatus, including in combination, a supporting frame, a sewing head supported on said frame and overhanging the front edge thereof, said sewing head including a stitching mechanism and an intermittent feeding mechanism, a horizontal support for the bottom of the bag disposed in advance of the front edge of said frame and under said sewing head, an endless conveyor located in front of said frame and above said bag support 80 for supporting and presenting the mouth of the bag to the sewing head and driving connections between the feeding mechanism of the sewing head and the endless conveyor for operating said mechanisms in synchronism and means whereby the sewing head, endless conveyor and bag support may be relatively adjusted vertically, said means including devices for maintaining the driving 85 connections in various adjusted positions.

7. A filled bag closing apparatus including in combination, a supporting frame, a sewing mechanism which includes a feeding mechanism and is supported on said frame and overhangs the front edge thereof, an endless bag conveyor located adjacent the bag mouth position for supporting and presenting the mouth of the bag to said sewing mechanism, means for moving said conveyor in synchronism with the feeding mechanism, and means for stripping the bag 90 from the endless conveyor.

8. A filled bag closing apparatus including in combination, a supporting frame, a sewing mechanism which includes a feeding mechanism and is supported on said frame and overhangs the front edge thereof, an endless bag conveyor located adjacent the bag mouth position for supporting and presenting the mouth of the bag to said sewing mechanism, means for moving said conveyor in synchronism with the feeding mechanism, said endless bag conveyor being provided with projecting pins on which the 105 mouth of the bag is impaled.

9. A filled bag sewing machine comprising a frame, a sewing head mounted on said frame and including a work arm and stitch forming mechanism, an endless traveling device having a plurality of projecting pins for supporting the bag mouth as it is being stitched, and means for intermittently mov-

ing said traveling device, said work arm having a groove formed therein to receive said traveling device and support the same.

10. A filled bag sewing machine comprising a frame, a sewing head and including a work arm, and stitch forming mechanism, an endless band, a supporting bracket, wheels mounted on said bracket and carrying said band, said band being disposed so as to move 10 across the work arm above the stitching point, a plurality of supporting pins carried by said band, and means for intermittently operating said band.

11. A filled bag sewing machine comprising a frame, a bag support, a sewing head overhanging said support and including a work arm and stitch forming mechanism, an endless band, a supporting bracket, wheels mounted on said bracket and carrying said 20 band, said band being disposed so as to move across the work arm above the stitching point, a plurality of supporting pins carried by said band, means for intermittently operating said band, and means for stripping 25 the bag from the pins after the bag has been stitched.

12. A filled bag sewing apparatus comprising a frame, an endless conveyor for supporting the filled bags and presenting the 30 same to the stitching mechanism, a sewing head carried by the frame and overhanging said endless conveyor, said sewing head including a stitching mechanism and a feeding mechanism, an endless belt having a plurality 35 of pins for engaging and supporting the mouth of the bag and presenting the same to the stitching mechanism, said endless belt being disposed above the feeding mechanism, and means for actuating the same in timing 40 with the feeding mechanism of the sewing head.

13. A filled bag sewing apparatus comprising a frame, an endless conveyor for supporting the filled bags and presenting the 45 same to the stitching mechanism, a sewing head carried by the frame and overhanging said endless conveyor, said sewing head including a stitching mechanism and a feeding mechanism, an endless belt having a plurality 50 of pins for engaging and supporting the mouth of the bag and presenting the same to the stitching mechanism, said endless belt being disposed at both the feeding in and the feeding out sides of the stitching 55 mechanisms, the said sewing head having a work supporting arm with a groove formed therein above the feed dog of the feeding mechanism for receiving and guiding said endless belt.

60 14. A filled bag sewing apparatus comprising a frame, an endless conveyor for supporting the filled bags and presenting the same to the stitching mechanism, a sewing head carried by the frame and overhanging 65 said endless conveyor, said sewing head in-

cluding a stitching mechanism and a feeding mechanism, an endless belt having a plurality of pins for engaging and supporting the mouth of the bag and presenting the same to the stitching mechanism, said endless belt 70 being disposed in front of and in rear of the stitching mechanisms the said sewing head having a work supporting arm with a groove formed therein above the feed dog of the feeding mechanism for receiving and guiding 75 said endless belt and common means for driving the sewing head, the endless belt and the conveyor for the filled bag.

15. A filled bag sewing apparatus comprising a frame, an endless conveyor for 80 supporting the filled bags and presenting the same to the stitching mechanism, a sewing head carried by the frame and overhanging said endless conveyor, said sewing head including a stitching mechanism and a feeding 85 mechanism, an endless belt having a plurality of pins for engaging and supporting the mouth of the bag and presenting the same to the stitching mechanism, said endless belt being disposed so as to travel in a plane parallel 90 with the plane of the supporting surfaces of the endless conveyor for the filled bag.

16. A filled bag sewing apparatus comprising a frame, an endless conveyor for 95 supporting and presenting the filled bags to the sewing mechanism, a sewing head carried by the frame and overhanging said endless conveyor, said sewing head including 100 stitching mechanism and feeding mechanism, means for operating said conveyor continuously, means for operating said feeding mechanism intermittently and in synchronization with the conveyor, an endless belt having 105 pins for engaging and supporting the mouth of the bag, and means for operating said endless belt in timing with the feeding mechanism and sewing mechanism.

17. A filled bag sewing apparatus comprising a frame, an endless conveyor for supporting the bag and presenting the same to a stitching mechanism, means for vertically adjusting said endless conveyor on said frame, a sewing head, a vertically adjustable bracket carried by the frame and supporting 110 said sewing head, said sewing head including stitching mechanism and feeding mechanism, an endless belt having a series of pins 115 for supporting the mouth of the bag and presenting the same to the stitching mechanism, and means for supporting said endless belt on said bracket whereby the same is vertically adjusted therewith.

In testimony whereof, I affix my signature, in the presence of two witnesses.

DUDLEY S. SEYMOUR.
